UNITED STATES PATENT OFFICE.

WILL A. CLARK, OF ST. LOUIS, MISSOURI.

LIQUID-POLISH APPLIER.

Application filed April 8, 1926. Serial No. 100,646.

This invention relates to liquid polish applicators and has for an important object thereof the provision of a device of this character which may be very readily and cheaply constructed and which will be durable and efficient in service.

A further object of the invention is to produce a device of this character having means for feeding to an applying pad a predetermined amount of liquid polish so constructed that the polish is very uniformly distributed upon the pad.

A further object of the invention is to provide in combination with a dispensing device of this character a hollow handle in communication with the dispensing device for containing a supply of the polish.

Other objects and advantages of the invention will become apparent throughout the course of the following description.

My invention is illustrated in the accompanying drawing, wherein:

Figure 1 is a longitudinal sectional view through a polish applicator constructed in accordance with my invention;

Figure 2 is an enlarged section on the line 2—2 of Figure 1;

Figure 3 is a section on the line 3—3 of Figure 2.

Referring now more particularly to the drawing, the numeral 10 indicates a cylinder, one end 11 of which is closed and the other end of which has a removable cap 12. The end 11 has a central opening 13 for coaction with a valve 14 carried by the lower end of a stem 15, the upper end of which projects through the cap 12 and has an actuating thumb-piece 16. Upon the stem within the cylinder is arranged a piston comprising a metal body 17 having a cork washer 18 applied thereto. Between the lower end 11 and the piston a spring 19 surrounds the stem and constantly urges the same upwardly and the body of the cylinder immediately beneath the lower end of the piston when in its raised position has openings 20 formed therein through which fluid polish may be fed from any suitable source. Beneath the cap a packing 21 is arranged for packing the stem 15 against possible leakage. The stem, when forced downwardly, to its lowermost position, unseats the valve and closes the openings 20, thereby preventing the entrance of further fluid from the source to the cylinder while forcibly ejecting the fluid already contained therein. A housing 22 is

removably connected to the upper end of the cylinder for the purpose of preventing accidental actuation of the stem.

Extending outwardly from the sides of the cylinder between the lower end thereof and openings 20 is a flange 23, the outer edges of which are provided with downturned flanges 24 which are exteriorly screw-threaded. A block 25 having a bore 26 fitting the cylinder is seated within the cap thus provided and is so constructed that it projects from the cap and is provided upon its exterior at this projecting portion with a downwardly facing shoulder 27. An interiorly and exteriorly threaded retaining ring 28 engages the threaded exterior of the flange 24 and at its lower end an inturned flange 29 for engagement against the shoulder 27 to maintain the block in position in the cap. That portion of the block seating within the cap is provided in its periphery with a groove 30, the purpose of which will presently appear.

The lower end of the bore 26 terminates in a downwardly tapering bore 31 and against the lower face of the block is seated a fiber washer pad 32, the opening of which likewise tapers downwardly and is very small at its lower end. This pad may be glued or otherwise secured to the block 25 and is covered, together with the block, by a cloth covering 33, the edges of which are maintained in position in the groove 30 during insertion of the block and pad by a small rubber band, indicated at 34. Once the block and pad together with the cover are in applied position, the cover will be maintained in its applied position by the engagement of the retaining ring 28 therewith. A cover for the applying pad or dauber thus produced is provided in a cup-shaped casing 35 having a threaded end 36 for engagement with the retaining ring 28 and having a shoulder for engaging the flange 29 of the retaining ring against which is seated a packing 37. This packing makes the cover air-tight, thereby preventing undue drying of the dauber. The supply for this cylinder is preferably in the form of a hollow tube 38, one end of which is permanently closed, as indicated at 39, and the opposite end of which has a removable screw cap 40 through which fluid may be replenished. The cylinder 10 is so positioned in the tube 38 that the openings 20 are immediately above the lower wall of the tube and fluid will flow

therethrough as long as there is any remaining in the tube.

In the use of the device, when the plunger is forced inwardly, the liquid polish is forcibly ejected from the cylinder by the piston which in its initial movement and at all times during its movement to and from the position in which the valve is closed seals the openings 20 to prevent the admission of further fluid to the cylinder. The valve, it will be noted, has its upper face tapered upwardly and the fluid escaping from the opening 13 and engaging against the tapered face of this valve is sprayed outwardly so that instead of impinging directly against the cover 33, it engages against the side walls of the opening of the pad and is absorbed by the felt layer 32. From this felt layer, it will be fed through the cover as pressure is applied to the pad in its movement over the shoe of the user. It will further be noted that the valve 14 at all times prevents direct spraying of the polish against the cover.

It will be obvious that many changes in the construction hereinbefore set forth may be resorted to without in any manner departing from the spirit of the invention and I accordingly do not limit myself to such specific structure except as hereinafter claimed.

I claim:

1. A dauber pad for use in applying polish comprising a cap having a central aperture for the passage of polish, a block fitting

the cap and having a groove formed in the side wall thereof in opposition to the side wall of the cap, said block having a central opening, a pad secured to the outer face of the block and likewise having a central opening, a porous covering for the pad and block, a retaining element engaging the covering and maintaining the same within the groove and means retaining the block, pad and covering in position within the cap. 45

2. A dauber pad for use in applying polish comprising a cap the side walls of which are exteriorly threaded and a central aperture for the passage of polish, a block fitting the cap and having a groove formed in the side wall thereof in opposition to the side wall of the cap, said block having a central opening, a pad secured to the outer face of the block and likewise having a central opening, a porous covering for the pad and block, a retaining element engaging the covering and maintaining the same within the groove and means retaining the block, pad and covering in position within the cap comprising a retaining ring interiorly threaded for engagement with the threaded outer wall of the cap, said ring having an in-turned flange, the block having a shoulder against which said flange engages to thereby clamp the block within the cap and to clamp 65 the covering to the block.

In testimony whereof I hereunto affix my signature.

WILL A. CLARK.
